(57) **CLAIM**

The ornamental design for a television receiver, as shown and described.

DESCRIPTION

FIG. 1 is a front, top, left perspective view of a television receiver showing our new design;

FIG. 2 is a front, bottom, left perspective view thereof;
FIG. 3 is a rear, bottom, right perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof;
FIG. 9 is a bottom plan view thereof;
FIG. 10 is a enlarged front, top, left perspective view thereof within the area designated as 10 of FIG. 1;
FIG. 11 is a enlarged front, top, left perspective view thereof within the area designated as 11 of FIG. 1;
FIG. 12 is a enlarged front, bottom, left perspective view thereof within the area designated as 12 of FIG. 2;
FIG. 13 is a enlarged front, bottom, left perspective view thereof within the area designated as 13 of FIG. 2;
FIG. 14 is a enlarged rear, bottom, right perspective view thereof within the area designated as 14 of FIG. 3
FIG. 15 is a enlarged rear, bottom, right perspective view thereof within the area designated as 15 of FIG. 3;
FIG. 16 is a enlarged front elevational view thereof within the area designated as 16 of FIG. 4;
FIG. 17 is a enlarged front elevational view thereof within the area designated as 17 of FIG. 4;
FIG. 18 is a enlarged rear elevational view thereof within the area designated as 18 of FIG. 5;
FIG. 19 is a enlarged rear elevational view thereof within the area designated as 19 of FIG. 5;
FIG. 20 is a enlarged bottom plan view thereof within the area designated as 20 of FIG. 9;
FIG. 21 is a enlarged bottom plan view thereof within the area designated as 21 of FIG. 9;
FIG. 22 is a enlarged bottom plan view thereof within the area designated as 22 of FIG. 9;
FIG. 23 is a front, top, left perspective view thereof, wherein the legs are in first alternate positions;
FIG. 24 is a front, bottom, left perspective view thereof;
FIG. 25 is a rear, top, left perspective view thereof;
FIG. 26 is a front elevational view thereof;
FIG. 27 is a rear elevational view thereof;
FIG. 28 is a left side elevational view thereof;
FIG. 29 is a right side elevational view thereof;
FIG. 30 is a top plan view thereof;
FIG. 31 is a bottom plan view thereof;
FIG. 32 is a enlarged front, top, left perspective view thereof within the area designated as 32 of FIG. 23;
FIG. 33 is a enlarged front, top, left perspective view thereof within the area designated as 33 of FIG. 23;
FIG. 34 is a enlarged front, bottom, left perspective view thereof within the area designated as 34 of FIG. 24;
FIG. 35 is a enlarged front, bottom, left perspective view thereof within the area designated as 35 of FIG. 24;
FIG. 36 is a enlarged rear, top, left perspective view thereof within the area designated as 36 of FIG. 25
FIG. 37 is a enlarged rear, top, left perspective view thereof within the area designated as 37 of FIG. 25;

FIG. 38 is a enlarged front elevational view thereof within the area designated as 38 of FIG. 26;
FIG. 39 is a enlarged front elevational view thereof within the area designated as 39 of FIG. 26;
FIG. 40 is a enlarged rear elevational view thereof within the area designated as 40 of FIG. 27;
FIG. 41 is a enlarged rear elevational view thereof within the area designated as 41 of FIG. 27;
FIG. 42 is a enlarged bottom plan view thereof within the area designated as 42 of FIG. 31;
FIG. 43 is a enlarged bottom plan view thereof within the area designated as 43 of FIG. 31; and
FIG. 44 is a enlarged bottom plan view thereof within the area designated as 44 of FIG. 31.
FIG. 45 is a front, top, left perspective view thereof, wherein the legs are in second alternate positions;
FIG. 46 is a front, bottom, left perspective view thereof;
FIG. 47 is a rear, bottom, left perspective view thereof;
FIG. 48 is a front elevational view thereof;
FIG. 49 is a rear elevational view thereof;
FIG. 50 is a left side elevational view thereof;
FIG. 51 is a right side elevational view thereof;
FIG. 52 is a top plan view thereof;
FIG. 53 is a bottom plan view thereof;
FIG. 54 is a enlarged front, top, left perspective view thereof within the area designated as 54 of FIG. 45;
FIG. 55 is a enlarged front, top, left perspective view thereof within the area designated as 55 of FIG. 45;
FIG. 56 is a enlarged front, bottom, left perspective view thereof within the area designated as 56 of FIG. 46;
FIG. 57 is a enlarged front, bottom, left perspective view thereof within the area designated as 57 of FIG. 46;
FIG. 58 is a enlarged rear, bottom, left perspective view thereof within the area designated as 58 of FIG. 47;
FIG. 59 is a enlarged rear, bottom, left perspective view thereof within the area designated as 60 of FIG. 47;
FIG. 60 is a enlarged front elevational view thereof within the area designated as 60 of FIG. 48;
FIG. 61 is a enlarged front elevational view thereof within the area designated as 61 of FIG. 48;
FIG. 62 is a enlarged rear elevational view thereof within the area designated as 62 of FIG. 49;
FIG. 63 is a enlarged rear elevational view thereof within the area designated as 63 of FIG. 49;
FIG. 64 is a enlarged bottom plan view thereof within the area designated as 64 of FIG. 50;
FIG. 65 is a enlarged bottom plan view thereof within the area designated as 65 of FIG. 50; and,
FIG. 66 is a enlarged bottom plan view thereof within the area designated as 66 of FIG. 50.
The broken lines illustrating portions of the television receiver form no part of the claimed design. The dot-dash broken lines illustrating boundaries of the claimed design form no part of the claimed design. The dot-dot-dash broken line rectangles depict limits of the enlarged views and form no part of the claimed design.
